A. ELMENDORF

MEANS OF JOINING METAL SHEATHED BOARDS ARRANGED EDGE TO EDGE

Filed May 23, 1921

Inventor:
Armin Elmendorf,
By Chamberlain & Brendenreick
Attns.

UNITED STATES PATENT OFFICE.

ARMIN ELMENDORF, OF CHICAGO, ILLINOIS, ASSIGNOR TO HASKELITE MANUFACTURING CORPORATION, A CORPORATION OF NEW YORK.

MEANS OF JOINING METAL-SHEATHED BOARDS ARRANGED EDGE TO EDGE.

Application filed May 23, 1921. Serial No. 471,925.

To all whom it may concern:

Be it known that I, ARMIN ELMENDORF, a citizen of the United States, residing at Chicago, county of Cook, State of Illinois, have invented a certain new and useful Improvement in Means of Joining Metal-Sheathed Boards Arranged Edge to Edge, and declare the following to be a full, clear, and exact description of the same, such as will enable others skilled in the art to which it pertains to make and use the same, reference being had to the accompanying drawings, which form a part of this specification.

My invention has for its object to produce a simple and novel means for fastening metal-sheathed boards together while arranged edge to edge, using the metal sheathing for this purpose and insuring that all exposed surfaces will be metallic.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a transverse section through two metal-sheathed boards adapted to be connected together edge to edge, showing the forms given them to permit the connection to be made;

Fig. 2 is a view similar to Fig. 1, showing the first step in the process of making the connection between the boards;

Fig. 3 is a view similar to Fig. 1 illustrating the second step in the process of fastening the boards together, the two edges having been brought in contact with each other;

Fig. 4 is a view similar to Fig. 3 showing the third step in the fastening process;

Fig. 5 is a section similar to Figs. 1 to 4, showing the completed joint.

Referring to the first five figures of the drawings, 1 and 2 represent the core members of two metal-sheathed boards, the member 1 having metal sheets or facings, 3 and 4, on opposite sides thereof while the member 2 is similarly provided with metal sheathings, 5 and 6, on opposed faces. The core members may be of any suitable mate-

rial in the form of sheets or boards of any desired thickness and of any desired number of layers, while the metal sheathings may have any desired thickness and be fastened to the cores in any desired way, preferably by being cemented thereto with a waterproof glue. The sheathing members 3 and 4 are extended beyond the edge of the core as indicated at 7 while the sheathing members 5 and 6 are extended beyond the edge of the core to which they are attached, the extensions or flanges, 8, being narrower than the extensions or flanges 7. The extensions or flanges 7 and 8 are first bent laterally in opposite directions as shown in Fig. 2. The two boards are then placed together with the flanges in contact with each other and the outer marginal portions of the flanges 7 are bent over the top and down beside the members 8 as shown in Figs. 3 and 4 respectively. Thus, there are formed three-ply ribs or projections on opposite faces of the work and these are then bent downwardly so as to lie flat as shown in Fig. 5.

It will thus be seen that I have produced a simple and novel construction and arrangement of parts which will permit the formation of simple flat panels out of a plurality of pieces of metal-sheathed board, the building of smooth-faced walls or signs supported by posts or the like which serve also as joint members, or the formation of shells of cylindrical or other shapes.

While I have illustrated and described only a few forms of my invention, I do not desire to be limited to the specific details thus illustrated and described; but intend to cover all forms and arrangements which come within the terms employed in the definitions of my invention constituting the appended claims.

I claim:

1. In combination, two boards arranged edge to edge and engaged with each other at the meeting edges, each board having glued thereto a metal sheathing element, 100 said metal sheathing elements being extended laterally of the boards at said meeting edges to form outwardly-directed flanges in engagement with each other.

2. In combination, two boards arranged 105 adjacent to each other in approximately the

same plane, each board having its opposed board faces plane at the edge confronting the adjacent edge of the other board and provided on each of said faces with a metal sheathing continued laterally of the boards at the adjoining edges of the latter to form outwardly-projecting flanges, said flanges

being bent and interlocked with each other to form flanges disposed outwardly of said plane portions and fastening said boards 10 rigidly together.

In testimony whereof, I sign this specification.

ARMIN ELMENDORF.
